US00D727359S

(12) **United States Design Patent**
Myung et al.

(10) **Patent No.:** US D727,359 S
(45) **Date of Patent:** ** Apr. 21, 2015

(54) **DISPLAY SCREEN OR PORTION THEREOF
WITH ICON**

(71) Applicant: **Samsung Electronics Co., Ltd.**,
Suwon-si (KR)

(72) Inventors: **Ji-Hye Myung**, Yongin-si (KR);
Bo-Hyun Sim, Incheon (KR);
Seock-Hyun Yu, Seoul (KR); **Jin-Young
Jeon**, Seoul (KR)

(73) Assignee: **Samsung Electronics Co., Ltd.**,
Suwon-si (KR)

(**) Term: **14 Years**

(21) Appl. No.: **29/456,003**

(22) Filed: **May 28, 2013**

(30) **Foreign Application Priority Data**

Mar. 27, 2013 (KR) 30-2013-0015493

(51) **LOC (10) Cl.** **14-04**

(52) **U.S. Cl.**

USPC **D14/495**; D14/491; D14/492

(58) **Field of Classification Search**

CPC .. G06F 3/0481; G06F 3/04817; G06F 3/0482
USPC D14/489-495

(57) **CLAIM**

The ornamental design for a display screen or portion thereof with icon, as shown and described.

DESCRIPTION

The sole FIGURE is a front view of a display screen or portion thereof with icon, showing our new design.

The broken line showing of the display screen is included for the purpose of illustrating environmental structure and forms no part of the claimed design.
